TUBE FRAME FOR AXMINSTER LOOMS

William W. Robertson, Northboro, Mass., assignor to Crompton & Knowles Loom Works, Worcester, Mass., a corporation of Massachusetts

Application December 20, 1937, Serial No. 180,727

6 Claims. (Cl. 139—10)

This invention relates to improvements in tube frames for Axminster looms and it is the general object of the invention to provide improved means for attaching the tube frame to the transporting chain.

As heretofore constructed tube frames have been provided with brackets or ears comprising two parts each of which engage a transporting chain. One of these parts is a guide ear which projects between the double links of the chain and is slotted to receive the second part which is in the form of a hook extending through the slot of the ear to lie over one of the links of the chain. The ear is generally provided with an offset at that part thereof which is slotted and the bending of the metal together with the slot weakens the ear to an extent which renders it inadequate for long and heavy tube frames.

In wide Axminster looms tube frames of the type used heretofore are subject to considerable vibration and furthermore the diameter of the yarn spools has been small. In order to permit the operation of wide Axminster looms at high rates of speed and at the same time carry a larger amount of tuft yarn than has been possible heretofore I propose to use a tube frame of increased cross section to provide the desired rigidity to resist vibration and also to support the greater weight of the spools. This increased weight is borne by the hooks which connect the tube frame to the chain when the tube frame hangs under the chain, and is supported by the ears when the tube frame is over the chain.

In order to provide a stronger means for attaching the tube frame to the chain I propose to mount the hook so that the same can slide relatively to the tube frame away from the ear without passing through the latter. By this construction the ear is solid throughout its length and is much stronger than corresponding ears used heretofore.

With the hook located behind the ear it is in a relatively inaccessible position for hand manipulation, and it is a further object of my invention to form the hook with finger holds projecting to a position where they can be reached by the weaver should he desire to remove a tube frame from the chain.

It is a further object of my invention to insert into the tubular bar of the tube frame a hollow block against which the hook support slides, thereby preventing wear of the more expensive tubular bar.

With these and other objects in view which will appear as the description proceeds, my invention

resides in the combination and arrangement of parts hereinafter described and set forth in the claims.

In the accompanying drawing wherein a convenient embodiment of my invention is set forth, 5

Fig. 1 is a front elevation of one end of the tube frame made according to my invention together with the spool and clutch, parts being in section;

Fig. 2 is an end elevation looking in the direction of arrow 2, Fig. 1, and

Fig. 3 is a vertical section through the top of a guide sprocket for the transporting chains, the tube frame being shown attached to the chain.

The tube frame forming the subject matter of 15 my present invention comprises a hollow rectangular bar 10 provided with a series of yarn tubes 11 and having a spool bearing 12 secured to the top thereof. This bearing receives the gudgeon 13 of a yarn spool S having a metallic head 14. 20

The transporting chain 20 is made up of pairs of links alternating with single links, the outer and inner links of any pair being shown at 21 and 22, respectively. The chain moves under a sprocket 23 which may be carried by the ordinary 25 pull-over shaft of an Axminster loom not shown. The chain is of the usual construction except that it may if desired be made heavier than the ordinary chain to carry the enlarged tube frame.

At each end of the loom there is a clutch C having 30 an upright wall 25 and a lower inwardly and downwardly inclined lip 26 to pass under the adjacent edge of the tube frame. The clutch may have wings one of which is shown at 27 to prevent lateral displacement of the tube frame and is 35 mounted by means of a pin 28 on a transporting lever 29. Oscillation of the clutch to effect the so-called wiping-in movements of the tube frame are effected by a second arm 30 connected pivotally to the clutch as at 31. A releasing lug 35 40 projects inwardly from the wall 25 for a purpose to be described. It is to be understood that the chain is moved one space for each tuft forming operation of the loom and that during this movement the clutch will be in the full line position 45 indicated in Fig. 1.

In carrying my invention into effect I provide a U-shaped slide block 40 having a vertical web 41 and top and bottom feet 42 and 43, which are capable of sliding along the top and bottom inner 50 flat surfaces 44 and 45, respectively, of the hollow bar. A hook 50 is welded to the slide block and a stud 51 has a reduced end which extends through the web 41 and the lower part of the hook to be headed over as at 52, thereby as 55

sisting in holding these two parts together. The top of the hollow bar is slotted as at 61 to permit inward sliding of the hook.

A hollow block 65 is secured within the end of the tube frame, as by welding, and has an inner wall 66 serving as a bearing for the left end of the stud 51. A spring 67 surrounding the pin and interposed between the web 66 and the wall 41 holds the hook yieldingly outwardly against the outer wall 68 of the hollow block, thus limiting outward motion of the hook but permitting the same to be moved inwardly against action of the spring 67. The side walls 69 of the block 65 lie against walls 55 of the tubular bar 10 and engage and guide the sides of parts 42 and 43 as the hook slides. Any wear resulting from sliding of block 40 occurs on walls 69 and not on the bar 10.

The ear or tongue E which projects between the links 21 and 22 may be formed substantially as shown in Figs. 1 and 2 and has the lower end thereof riveted as at 70 to the wall 68. The ear extends upwardly and may be offset slightly as at 71 to have a straight upper end 72. The hook 50 has a bent upper end 73 to lie over the link 22, and the relation between the end 73 and the straight end 72 of the ear is very similar to that heretofore used.

In the past it has been customary, however, to mount a part of the hook outside of the ear, but it will be seen by reference to Fig. 1 that I locate all parts of the hook to the left of the ear E. The lower end of the ear is perforated as at 80 and the wall 68 has a second aligning perforation 81, see Fig. 1, to receive the release lug 35 carried by the clutch.

In the operation of that part of my invention thus far described the parts will normally be in the full line position shown in Fig. 1 and as the clutch moves to the left to assume the dotted line position shown in that figure the releasing lug 35 will pass through the perforations 80 and 81 and bear against the end of the pin 51, thereby causing the block 40 and the hook to slide inwardly 45 toward the center of the loom. This is accompanied by movement of the bent end 73 to the left of link 22, after which the clutch may be lowered in the usual manner to present the tube frame to tuft forming position. It is customary 50 to form the lip 26 so that as the clutch moves in the tube frame is lifted slightly to permit clearance of the hooked end 73 with respect to the link 22, and I retain this feature in my present construction. After the row of tufts has been 55 formed the clutch moves up toward the chain and the straight end 72 will enter between links 21 and 22, after which the clutch will move away from the tube frame and spring 67 will push the hook from the dotted position of Fig. 1 back to the full line position.

Because of the shape of the ear 71 I find it desirable to modify the construction of the ordinary sprocket 100 found in the overhead of Axminster looms to the extent indicated in Fig. 3. In this figure, where a section is shown through the sprocket at one of the double links, the body of the sprocket is offset as at 105 to define a pocket 106 into which the ear E may pass as the tube frame moves up on one side of the sprocket. Sprocket 100 is additional to the pull-over sprocket 23 and is located in the chain supporting rack generally located above and behind the loom proper.

The tongue 72 of the ear has the usual rounded

shoulders 103 to engage adjacent edges of the single links lying between the double links 21 and 22. These shoulders perform their usual function of preventing excess vibration of the tube frame relatively to the transporting chain. 5

In order to detach a tube frame from the chain the weaver must push the hook 50 inwardly. Since it lies behind the ear E and is narrower than the ear it is relatively inaccessible. To facilitate this operation I form lugs 110 on the 10 hook, these lugs projecting far enough laterally from the hook to be reached by the weaver.

The parts attached to ear E and extending inside the tubular bar restrain angular motion of the ear relatively to the bar, but this is not 15 the only means by which this result can be accomplished, as will be apparent from copending application filed by Payne, Serial No. 180,805.

From the foregoing it will be seen that I have provided a tube frame construction permitting 20 the use of a heavier bar and also a larger spool, the attaching means for the chain constituting two parts which do not cross each other and do not extend through each other. This result is accomplished by having the hook lie entirely 25 at one side of the ear and mounting the hook on a block which is slidable within the hollow bar of the tube frame. It will be apparent from Figs. 1 and 2 that the ear is of considerable 30 strength and can support the increased weight of the tube frame due to the larger bar 10 and spool S. Furthermore, the side walls of block 65 engage the parts 42 and 43 of the block 40 to prevent wear of the bar 10. Also, the lugs 110 facilitate manual release of a tube frame from 35 the chain.

Having thus described my invention it will be seen that changes and modifications may be made therein by those skilled in the art without departing from the spirit and scope of the invention and I do not wish to be limited to the details herein disclosed, but what I claim is:

1. In an Axminster loom having a transporting chain, a tube frame, a bracket secured to the tube frame and extending into engaging relation with respect to the chain, a hook to engage the chain located wholly on that side of the bracket which faces the longitudinal center of the tube frame, means defining a sliding bearing between the hook and the tube frame, and means 45 to move the hook away from the ear toward the center of the tube frame.

2. In an Axminster loom having a transporting chain, a tube frame including a hollow carrier bar rectangular in cross section, an ear fixed 55 with respect to the bar and extending laterally therefrom to engage the chain, a hook for the chain located wholly on that side of the ear facing the longitudinal center of the bar, a slide- 60 able bearing block fixed to the hook and located inside the carrier bar, said bearing block engaging interior surfaces of the carrier bar to prevent rotation of the hook in a plane trans- 65 verse of the axis of the bar, and means to move the block and hook longitudinally of the bar to- 70 ward the center of the tube frame and away from the ear.

3. In an Axminster loom having a transporting chain, a tube frame comprising a hollow carrier bar rectangular in cross section, an ear for 75 the tube frame engaging the chain, a bearing member to which the ear is fastened, said bearing member being secured to the carrier bar and located inside the latter, a hook for engagement with the chain located entirely on that side of 75

the ear which faces the longitudinal center of the carrier bar, a cylindrical guide element secured to the hook and extending through the guide bearing, and a block secured to the hook to engage interior surfaces of the carrier bar to prevent substantial angular motion of the hook in a plane transverse to the axis of the bar.

5. In an Axminster loom having a transporting chain, a tube frame comprising a hollow carrier bar rectangular in cross section, an ear for the tube frame to engage the chain, a bearing member to which the ear is fastened, said bearing member being secured to the carrier bar and located inside the latter, a hook for engagement with the chain located entirely on that side of the ear which faces the longitudinal center of the carrier bar, a cylindrical guide element secured to the hook and extending through the guide bearing, and a block secured to the hook to engage interior surfaces of the slide bearing to prevent substantial angular motion of the hook in a plane transverse of the axis of the carrier bar.

10. In an Axminster loom having a transporting chain, a tube frame comprising a hollow carrier bar rectangular in cross section, an ear for the tube frame to engage the chain, a bearing member to which the ear is fastened, said bearing member being secured to the carrier bar and located inside the latter, a hook for engagement with the chain located entirely on that side of the ear which faces the longitudinal center of the carrier bar, a cylindrical guide element secured to the hook and extending through the guide bearing, and a block secured to the hook to engage interior surfaces of the slide bearing to prevent substantial angular motion of the hook in a plane transverse of the axis of the carrier bar.

15. In an Axminster loom having a transporting chain, a tube frame comprising a hollow carrier bar rectangular in cross section, an ear for the tube frame to engage the chain, a bearing member to which the ear is fastened, said bearing member being secured to the carrier bar and located inside the latter, a hook for engagement with the chain located entirely on that side of the ear which faces the longitudinal center of the carrier bar, a cylindrical guide element secured to the hook and extending through the guide bearing, and a block secured to the hook to engage interior surfaces of the slide bearing to prevent substantial angular motion of the hook in a plane transverse of the axis of the carrier bar.

20. In an Axminster loom having a transporting chain, a tube frame comprising a hollow carrier bar rectangular in cross section, an ear for the tube frame to engage the chain, a bearing member to which the ear is fastened, said bearing member being secured to the carrier bar and located inside the latter, a hook for engagement with the chain located entirely on that side of the ear which faces the longitudinal center of the carrier bar, a cylindrical guide element secured to the hook and extending through the guide bearing, and a block secured to the hook to engage interior surfaces of the slide bearing to prevent substantial angular motion of the hook in a plane transverse of the axis of the carrier bar.

25. In an Axminster loom having a transporting chain, a tube frame comprising a hollow carrier bar rectangular in cross section, an ear for the tube frame to engage the chain, a bearing member to which the ear is fastened, said bearing member being secured to the carrier bar and located inside the latter, a hook for engagement with the chain located entirely on that side of the ear which faces the longitudinal center of the carrier bar, a cylindrical guide element secured to the hook and extending through the guide bearing, and a block secured to the hook to engage interior surfaces of the slide bearing to prevent substantial angular motion of the hook in a plane transverse of the axis of the carrier bar.

a hollow block secured to the ear and extending into and fixed with respect to the carrier bar, a hook located wholly between the ear and the longitudinal center of the bar, and sliding guide means carried by the hook and located within the hollow block, said sliding guiding means slideable along interior surfaces of the hollow block to move the hook from the ear toward the center of the tube frame and away from the chain.

5. In an Axminster loom having a transporting chain, a tube frame, an ear fixed with respect to the tube frame and extending toward the chain, said ear being of a substantially uniform width throughout the greater part of the length thereof between the tube frame and the chain, a hook for the tube frame located wholly on that side of the ear which faces the longitudinal center of the tube frame, sliding connections between the hook and the tube frame, said hook being of substantially less width than the ear, and projections extending laterally from the hook to constitute hand holds accessible from that face of the ear remote from the longitudinal center of the tube frame to permit manual sliding of the hook relatively to the tube frame.
